EXPLOSIVE COMPOSITION

George C. Hale, Dover, N. J.

No Drawing. Application October 30, 1943,
Serial No. 508,387

5 Claims. (Cl. 52—13)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to an explosive.

The explosive, ethylenedinitramine, covered by U. S. Patent 2,011,578 granted to me, has a melting point of approximately 175° C. which makes impracticable the loading of this explosive into shell or bombs by casting methods. This constitutes a definite limitation on the practical application of the explosive in ammunition components since many of these cannot be loaded economically by pressing or tamping the explosive charge to give the high density required.

I have discovered that ethylenedinitramine is only slightly soluble in trinitrotoluene (TNT) and that mixtures of the two explosives can be prepared which can be loaded by the usual casting methods employed in loading shell and bombs. Mixtures containing more than 40% TNT with the remainder ethylenedinitramine can be rendered sufficiently fluid upon heating with low pressure steam, such as in the neighborhood of 25 lbs. pressure or less to permit pouring of the composition into any standard type of shell or bomb. In this composition at the casting temperature 90—100° C., ethylenedinitramine is in suspension in the liquid TNT which serves as a vehicle or carrier for the crystalline or granular dinitramine. Upon cooling in the bomb or shell, the charge solidifies to a compact mass having a density of about 1.60.

I have found from extensive tests that the casting composition containing 58% ethylenedinitramine and 42% TNT is not only practicable from the standpoint of loading by casting methods but is an explosive having certain special properties which render it highly favorable for general military use as a bursting charge. When 3" A. A. shell were loaded with the casting composition and fired using the standard fuze, the average total number of fragments produced was 584 as compared to a total of 413 given by shell of the same lot loaded with TNT. This shows that the new explosive has much higher brisance or fragmenting effect than TNT, the increase in number of effective fragments being approximately 41% over that given by TNT.

2

The stability of the explosive is entirely satisfactory as shown by the fact that there was no ignition, no fuming or other indication of instability when samples were heated at 100° C. for 100 hours.

Extensive tests to determine the sensitivity of the new explosive showed that it did not detonate under the steel shoe in the standard pendulum friction test and was not ignited or detonated by rifle fire when subjected to the standard rifle bullet impact test. This explosive composition containing ethylenedinitramine and TNT is the only explosive known to me which has higher brisant effects than TNT and yet does not detonate when subjected to impact of a rifle bullet under the standard test conditions. This property is most unusual and of considerable importance from the standpoint of military use.

In addition to the favorable properties above mentioned the new explosive composition does not absorb moisture from the air under extreme conditions of temperature and humidity and has shown no reaction when in contact with aluminum, steel and brass after exposure for more than 20 months in surveillance chambers maintained at 50° C.

While I have indicated that a composition comprising about 58% of ethylenedinitramine and 42% of TNT is a preferred composition for general use as a bursting charge, it is recognized that in particular ammunition components it is sometimes advisable to sacrifice with respect to one particular property of an explosive in order to obtain some special effect. Thus, the high brisance of the 58/42 composition may not be an essential requirement in a particular application but a greater degree of insensitivity is of importance. I have found that such can be obtained by increasing the TNT in the composition above 42%. Such mixtures of higher TNT content are as readily adaptable to loading conditions, are less sensitive to shock and friction and are inferior to the preferred composition only with respect to brisance or shattering effect.

45 I claim:

1. An explosive composition comprising a mixture of ethylenedinitramine and trinitrotoluene in which the trinitrotoluene forms over 40 percent of said mixture and the ethylenedinitramine constitutes the remainder of said mixture.

2. An explosive composition, which is sufficiently fluid at about 90-100° C. to be cast, comprising a mixture of about 58 parts of ethylenedinitramine and about 42 parts of trinitrotoluene.

3. An explosive composition consisting of 58 parts of ethylenedinitramine and 42 parts of trinitrotoluene.

4. A castable explosive composition formed by heating more than 40 per cent of trinitrotoluene with ethylenedinitramine.

5. A fluid suitable for pouring into cavities of explosive missiles comprising more than 40 percent of trinitrotoluene and the remainder ethylenedinitramine.

GEORGE C. HALE.
